UNITED STATES PATENT OFFICE.

HUGO HENKEL AND HENRY STERNITZKE, OF CHICAGO, ILLINOIS.

SHADE HOLDER.

Application filed February 27, 1922. Serial No. 539,375.

To all whom it may concern:

Be it known that we, HUGO HENKEL and HENRY STERNITZKE, citizens of the United States, and residents of Chicago, in the 5 county of Cook and State of Illinois, have invented certain new and useful Improvements in a Shade Holder, of which the following is a specification.

Our invention relates to an improved 10 shade holder and has special reference to improved means for retaining a shade in a holder.

The object of our invention is to provide a shade holder in which a shade can be readily 15 and easily mounted; which shall not depend upon screws for holding the shade in place; and from which the shade can be freely, easily and quickly removed when desired.

A feature of importance resides in the 20 provision of yielding supports for the shade and a pivoted shade engaging latch, the parts being of simple and cheap construction and readily assembled with the holder ring.

25 Our invention will be more readily understood by reference to the accompanying drawings forming part of this specification, and in which:

Figure 1 is a top plan view of a shade 30 holder constructed in accordance with our invention;

Figure 2 is a vertical central sectional view on the line 2—2 of Figure 1 showing a fragmentary section of a shade held in the 35 holder.

Figure 3 is a horizontal section on the line 3—3 of Figure 2;

Figure 4 is a side elevation of the holder; and

40 Figure 5 is a fragmentary horizontal section on the line 5—5 of Figure 2.

In said drawings 1 illustrates our improved holder having a main body portion made of a single piece of sheet metal formed 45 into an outer depending ring 2 for receiving the base 3 of a shade 4, an inner ring 5 having radial lugs 6 adapting the holder to be clamped upon a support such as an incandescent electric lamp socket and the two

50 rings connected and joined by a substantially flat web portion 7. The ring 5 may be secured to the lamp holder by any suitable means such as a clamping bolt or screw 8 passing through the lugs 6.

55 The base 3 of the shade 4 is slightly larger at its edge 9 than just below the edge as at

10 and we arrange shade supports within the outer or marginal ring 2 adapted to engage the shade below its enlarged upper end.

These shade supports comprise a flat 60 spring 11 at one side and a latch member 12 at the other side. The spring 11 is flat and is secured at its middle point to the ring 2 by a rivet 13. This spring is made of greater curvature than the base of the 65 shade as indicated in dotted lines in Figure 3 and its two ends 14 contact with the shade at circumferentially spaced points below the curved out base of the shade. The spring lies entirely within the ring 2 out of sight. 70

The latch 12 comprises a hooked member made of sheet metal having a hooked lower end 15 adapted to extend around the lower edge of the ring 2, the inner free end 16 rising within the ring 2 and adapted to engage the base of the shade at a point substantially on the line of the upper edge of the spring 11. The latch is pivotally mounted on the holder by means of two bent lugs or projections 17 which are adapted to 80 project through slots 18 in the ring 2. Each of the projections 17 is perforated at its inner end to receive a retaining pin 19. The pin is projected through both the perforations in the projections after they have 85 been entered through the slots 18 and then the free end 20 of the pin is bent over to prevent the pin working out. The outer end 21 of the latch member rises above the projections 17 and is bent inwardly so that 90 when the latch is in shade supporting position as shown in Figure 2, the upper end 21 of the latch contacts with the upper edge of the ring 2. The extreme upper end 22 of the end 21 of the latch member rises 95 above the ring 2 at its connection with the web portion 7 so that it can be readily engaged by the finger when it is desired to release the shade for pulling this upper end outwardly. The inner end 16 of the latch member is inclined inwardly when in shade supporting position and is adapted to be swung to vertical position and close to the inner surface of the ring 2 when it is desired to release the shade. 100

To insert a shade in the holder it is merely necessary to grasp the shade, inserting one edge of the base into the ring 2 against the spring 11 when a slight sidewise pressure will force the ends 14 of the spring back 110 toward the ring 2 so that the opposite edge of the shade can be readily raised into the

ring 2. Such action tends to swing the inner end 16 of the latch outwardly and the adjacent edge of the base of the shade readily passes above the inner end of the latch. The weight of the inner end of the latch tends to tip the latch to lower its inner end to the position shown in Figure 2 as soon as the base of the shade has passed the latch and thus the latch automatically locks the shade in place. The outer end 21 being bent inwardly aids this automatic dropping of the latch. Preferably the inner end 16 of the latch is curved slightly horizontally as shown at 23 to best engage the shade base. To remove the shade from the holder it is merely necessary to pull the outer upper end 22 of the latch outwardly thus lifting and swinging outwardly the inner end 16 and then if the base of the shade is not free to be removed, the shade can be pushed laterally by slight sidewise pressure, thus forcing back the spring 11 so that the edge of the base of the shade will freely pass the latch. It will now be understood that our holder is very simple in its construction, that it can be made very cheaply and that shades can be

readily and easily inserted and removed. It is to be noted that the weight of the shade tends to retain the latch in shade locking position.

As many modifications of our invention will readily suggest themselves to one skilled in the art, we do not limit or confine our invention to the specific details of construction herein shown and described.

We claim:

In a shade holder of the kind described, a supporting ring adapted to encircle the base of a shade, a flat spring member secured in the ring at its middle point, its free ends forming two separated supports for the shade, a latch comprising a hook adapted to encircle the lower edge of the ring, bent projections on the hook adapted to extend through slots in the ring, means for holding the projections in the slots, the outer end of the latch forming a finger hold for swinging the latch to release the shade.

Signed at Chicago, Illinois, this 23rd day of February, 1922.

HUGO HENKEL.
HENRY STERNITZKE.
